GARMENT HANGER

Bartlett F. Vavruska, Prairie du Chien, Wis.

Application October 29, 1934, Serial No. 750,573

6 Claims. (Cl. 223—64)

This invention relates to an improved garment hanger and has more particular reference to the so-called combination type, that is the form of hanger which embodies the conventionally shaped arcuate coat hanger equipped with a trouser clamp.

By way of comparison with prior marketed and similar prior art structures it will be observed from the accompanying drawings and descriptive matter that novelty is predicated in one instance on the particular construction of the longitudinally extensible and contractible coat hanger provided with a special swivelly mounted suspension hook located to provide the requisite balance and adaptation when extended from its compact retracted position to its elongated or full operating position.

Of equal importance in the structural arrangement is the especially constructed trousers hanger characterized by a backing plate, a spring opened pivotally mounted clamping member carried thereby, and a pair of duplicate adapters mechanically fashioned and co-related with respect to the other parts to serve as a means for securely holding the clamping member in trousers clamping position, or allowing it to be expeditiously swung to open position for reception of the cuff portions of the trousers.

Other structural features and accompanying advantages will become more readily apparent from the following description and drawings.

In the drawings:

Figure 1 is a front elevational view of the complete structure showing the trousers clamp closed and the garment or coat hanger extended to its customary functioning position.

Figure 2 is a top plan or edge view of Figure 1.

Figure 3 is a view similar to Figure 1 observing the opposite side thereof and showing the companion sections of the coat hanger contracted into folded or compact positions.

Figure 4 is an enlarged sectional and elevational view showing one of the adapters as swung to a releasing position and also showing the trousers clamping unit swung to its open trousers insertion position.

The coat hanger per se is represented as a unit by the numeral 5 whereas the complementary trousers hanger is differentiated, as a unitary structure, by the numeral 6. Considering then the coat hanger 5 it is preferably of light weight metal and comprises a pair of duplicate arcuate metal strips 7 and 8 disposed in overlapping slideable relation and having their inner adjacent ends telescopically connected together in any

suitable manner as indicated for example, at 9. The outer end portions are formed with elongated adjusting slots 10 slidably connected with the headed upper ends 11 of rod members 12 which may be conveniently denoted as posts or pins. 15 The lower ends of these are reduced as indicated at 13 and function as journals in a manner to be hereinafter described. This arrangement allows the sections 7 and 8 to be slid on each other which makes it possible to either contract the coat hanger in the manner shown in Figure 3 or extend it to the operating position shown in Figures 1 and 2. As seen in Figure 3 the numeral 14 designates the pivoted clip with which the shank of the suspension hook 15 is swivelly connected. This 10 makes the hook substantially self-leveling and by attaching the clip 14 to one end portion of the section 7 for example, it is obvious that when the sections are extended to the full length position shown in Figures 1 and 2 this disposes the suspension hook in the proper centralized position to be hung on a closet hook, nail or the like. 15

Considering now in detail the construction of the trousers hanger 6 as a unit, I call attention first to the main or relatively stationary plate 16 which may be distinguished as a backing plate. This is of general rectangular form and provided adjacent its opposite ends with pairs of out struck tongues 17 and 18 which function as ears and with which complementary ears 19 are pivotally connected through the instrumentality of a pivoting and connecting pin 20. The ears 19 are bent laterally from the plate like end members 21 on the opposite ends of the somewhat flexible and relatively movable clamping strap 22. Or stated otherwise, this strap 22 which cooperates with the backing plate is provided at its ends with attaching members 21 which are in turn provided with ears 19 pivotally attached to the ears 17 and 18 by way of the pins 20. This provides the desired swingable or pivotal connection between the parts 16 and 22 allowing them to function as a clamp between which the cuff portions of the trousers may be clamped in a well known manner. 20

It will be noted that at one end there is a coiled spring 23 and this surrounds the pin at the right of Figures 1 and 2 and is so arranged as to press or exert an outward pressure on the adjacent member 21 and to thereby swing the clamping strap 22 outwardly to its open or trousers insertion position. (See Figure 4.) 25

Novel means is provided for closing the clamping member 22 and retaining it in closed position. It is to be noted first, however, that the 30

55

upper end portions of the end members 21 of the strap serve as stops as indicated at 24. Moreover these upper end portions are provided with flat holding springs 25. The tension of the 5 springs may be regulated by set screws 26. These springs are adapted for cooperation with the cam like edges 27 on the latch fingers 28 carried by the wing like adapters 29. The adapters are more in the nature of flaps or wings and are provided with flanges 30 whose inner end portions straddle and are pivotally connected to the aforesaid pintles 13. As a matter of fact, the end portions of the backing plate 16 are also provided with reinforcing flanges 31 and the pintles 13 extend 10 through these flanges and also the flanges 30 providing the requisite swingable or pivotal connection between the adapters 29 and the backing plate. One of the adapters is shown in Figure 4 and it is swung to open position and when 15 in this position it serves to disengage the latch 28 from the adjacent leaf spring 25 on the stop edge 24. Consequently, the spring 23 then comes into play automatically to force the clamping member 22 to its open position and this facilitates 20 insertion of the cuff portions of the trousers. When the cuff portions are thus disposed between the parts 16 and 22 it is possible to catch hold of the adapter 29 at one end and to swing it around from the position shown in Figure 4 to 25 the position shown in Figures 1 and 2 and this cooperates with the adjacent spring 25 in providing a cam action to swing the part 22 closed against the tension of the coiled spring 23. The presence of the cam edge 27 and the spring 25 makes this cam action more effective and smooth. 30 Moreover, it allows the clamping member 22 to be mechanically forced to its clamping position. Otherwise, it would be inconvenient to place the cuff portions of the trousers between the two parts 16 and 22. It is desirable to provide two of 35 these adapters 29 and it is obvious that they are of duplicate construction and identically mounted. In a sense, these adapters serve as relatively wide handles for the latches 28. In other words, 40 it is the latch 28 which is most important but by providing a relatively large plate like adapter 29 the latter part serves as a sort of handle or finger grip and makes it possible to actuate the parts 45 with less trouble.

50 It is evident that novelty is attached to the special selection and coordination of the backing plate 16 having the end flanges 31 carrying the flanged adapters 29, these adapters having latch members or fingers and the flange portions of 55 these parts being connected together by way of the journal pins 13. Added to this is the novelty of the complementary pivotally mounted clamping strap or plate 22 having the especially designed end portions 21 one of which is forced out by a 60 spring 23 and both of which are provided with the retention springs 25 located to cooperate with the cam edges 27 of the latch fingers 28. This, it is believed, is an ingenious arrangement and is especially suited for the purposes intended.

65 Additional novelty is predicated on the idea of an extensible and retractible coat hanger, with the swivelly mounted suspension hook, having adjustable connections with the posts or pins 12 serving as means for joining the two parts 70 5 and 6 in operative relationship. Considering this arrangement as a composite structure it provides an unusual combination coat hanger and trousers hanger. Moreover, the parts are so successfully coordinated as to make it possible to attach and detach the trousers with the 75

least possible trouble. I shall not, however, delve into the commercial aspects of the invention since it is the particular construction and arrangement which forms the principal novelty distinguishing the structure in part and in whole from similar prior art and marketed devices. 5

It is thought that persons skilled in the art to which the invention relates will be able to obtain a clear understanding of the invention after considering the description in connection with 10 the drawings. Therefore, a more lengthy description is regarded as unnecessary.

Minor changes in shape, size and rearrangement of details coming within the field of invention claimed may be resorted to in actual 15 practice, if desired.

Having thus described the invention, what is claimed as new is:

1. In a structural assemblage of the class described, in combination, a longitudinally bowed 20 coat hanger comprising a pair of sections disposed in slidable overlapping relationship, a clip pivotally connected with one of said strips, a suspension hook swivelly connected with said clip, a trousers supporting and clamping unit, 25 rod connections between said unit and the companion sections of said coat hanger unit, said connections having slidable connection with the hanger sections.

2. A structural assemblage of the class de- 30 scribed comprising, in combination, a trousers supporting and clamping unit comprising a backing plate, a clamping member pivotally attached to said plate, retaining and releasing latch means pivotally attached to the end por- 35 tions of said backing plate and cooperable with the adjacent end portions of said clamping member, and spring means interposed between the backing plate and clamping member, said spring means serving to swing the clamping 40 member to open trousers reception position when the latch means is manually released.

3. In a structural assemblage of the class de- 45 scribed comprising, in combination, a trousers supporting and clamping unit comprising a backing plate, a clamping member pivotally attached to said plate, retaining and releasing latch means pivotally attached to the end por- 50 tions of said backing plate and cooperable with the adjacent end portions of said clamping mem- 55 ber, and spring means interposed between the backing plate and clamping member, said spring means serving to swing the clamping member to open trousers reception position when the latch means is manually released, connecting pins associated with the end portions of said 60 backing plate and having headed upper end portions, a coat hanger unit embodying slidably connecting sections and a suspension hook, said sections having slots slidably engageable with said headed end portions of the connecting pins.

4. In a structure of the class described, a trousers clamping and supporting unit comprising a backing plate, a complementary clamping member pivotally connected at its ends to said backing plate in a manner to allow the cuff portions of the trousers to be clamped between the backing plate and clamping member, spring means associated with said backing plate and clamping member for automatically swinging the clamping member to open position, operating members pivotally connected to the end portions of said backing plate and provided with latch fingers engageable with the adjacent end 75

portions of said clamping member to hold the clamping member and to facilitate its closing.

5. In a structure of the class described, a backing plate, a clamping member pivotally attached at its end portions to said backing plate, spring means interposed between the backing plate and clamping member to swing the clamping member open, the ends of said clamping member being provided with stop elements having adjustable friction leaf springs, plate like adapters pivotally connected to the ends of said backing plate and provided with laterally directed latch fingers, said latch fingers having cam edges located for cooperating contacts with said leaf springs.
6. In a structure of the class described, a backing plate, a spring pressed pivotally mounted clamping member on said backing plate, wing like members pivotally connected to the ends of said backing plate provided with cam latches engageable with the adjacent end portions of said clamping member, and spring means interposed between the backing plate and clamping member in the manner and for the purposes described. 5 10
